United States Patent Office

Des. 175,123
Patented July 12, 1955

175,123

ALTAR

Donald R. Maxwell, Edwardsburg, Mich.

Application December 14, 1954, Serial No. 33,547

Term of patent 3½ years

(Cl. D29—23)

Fig. 1.

Fig. 2.

Fig. 3.

Figure 3 is a top plan of the altar of Figures 1 and 2. The back of the altar is plain.

I claim:

The ornamental design for an altar, as shown and described.
